UNITED STATES PATENT OFFICE.

MICHAEL G. MCGUIRE, OF NIAGARA FALLS, NEW YORK.

UMBRELLA-RIB.

No. 895,390.

Specification of Letters Patent.

Patented Aug. 4, 1908.

Application filed November 26, 1907. Serial No. 403,893.

To all whom it may concern:

Be it known that I, MICHAEL G. MCGUIRE, a citizen of the United States, residing at Niagara Falls, in the county of Niagara and State of New York, have invented new and useful Improvements in Umbrella-Ribs, of which the following is a specification.

This invention relates to ribs for umbrellas and parasols, and is designed, primarily, as an improvement upon the form of umbrella rib and brace, as set forth in Letters Patent granted to me May 21, 1907 No. 854,663; and the object thereof is to provide, in a manner as hereinafter set forth, what may be termed a combined umbrella rib and brace embodying a rib member and a brace member suitably connected together so that one member is adapted to reinforce the other, whereby an umbrella rib of unusual strength is provided so that when a plurality of ribs in accordance with this invention is used in connection with an umbrella and when the umbrella embodying such ribs is extended, it will, owing to the rib construction, possess unusual rigidity so as not to collapse or be turned inside-out by sudden gusts of wind.

A further object of the invention is to provide an umbrella rib, in a manner as hereinafter set forth, and which embodies a rib member and a brace member, said members being flexible, as well as resilient, whereby when a plurality of ribs in accordance with this invention forms a part of an umbrella and when the lower ends are released during the act of opening the umbrella, the lower portions of the ribs will be caused to project away from the stick of the umbrella thereby facilitating the opening thereof.

A further object of the invention is to provide an umbrella rib, in a manner as hereinafter set forth, and which embodies a rib member and a brace member, said brace member being positioned above the rib member, connected to the lower end of the rib member, slidably connected to the rib member at a point removed from its upper end, and so constructed as to receive the rib member as an entirety when the umbrella is closed, offering no obstacle to permit compact rolling after the umbrella has been closed, said brace member further acting as a continuation of the rib member when the rib member is extended, whereby an internal support is provided for that portion of the umbrella cover which is arranged above and not attached to the rib member.

Further objects of the invention reside in the providing of a sectional umbrella rib which shall be unusually strong and with one section receiving and reinforcing the other section, durable, possessing the necessary resiliency to facilitate the opening of the umbrella when the ribs are released, allowing of a compact folding of the umbrella, capable of being readily attached to a runner and notched collar, simple in construction, readily assembled and comparatively inexpensive to manufacture.

With the foregoing and other objects in view, the invention consists of the novel construction, combination and arrangement of parts hereinafter more specifically described and illustrated in the accompanying drawings wherein is shown the preferred embodiment of the invention, but it is to be understood that changes, variations and modifications can be resorted to which come within the scope of the claims hereunto appended.

In the accompanying drawings, wherein like reference characters denote corresponding parts throughout the several views—

Figure 1 is a longitudinal sectional view of my umbrella rib in accordance with this invention, showing the same connected with the umbrella stick; Fig. 2 is a section on line 2—2 of Fig. 1; Fig. 3 is a section on line 3—3 of Fig. 1; Fig. 4 is a section on line 4—4 of Fig. 1; Fig. 5 is a side elevation of a rib in accordance with this invention; Fig. 6 is an inverted plan of the brace member of the rib; Fig. 7 is an inverted plan of a modified form of brace member; Fig. 8 is a section on line 8—8 of Fig. 7, and, Fig. 9 is a section on line 9—9 of Fig. 7.

Referring to the drawings in detail, 1 denotes the umbrella stick upon which is mounted a runner 2 having a notch 3 whereby the runner 2 can take over the latch 4 carried by the stick. The runner 2 is of that class which is shifted towards the handle end 100 of the umbrella when opening the latter. Fixed to the stick 1 is a notched collar 5. Upon the outer end of the stick is carried a ferrule 6. The foregoing elements are of known construction and are illustrated so that the adaptation of an umbrella rib in accordance with this invention can be thoroughly understood.

An umbrella rib in accordance with this invention embodies a rib member 7 and a brace member 8, each of which is formed of a suitable resilient material. The rib member

7 at its upper end is provided with an eye as at 9, whereby said upper end of the member 7 can be pivotally connected as at 10 to the runner 2. The rib member 7 is connected at its lower end and at a point removed from its upper end to the brace member 8. When the umbrella is extended the portion of the rib member 7 between the two points of connection nests within the brace member 8 and when the umbrella is closed the rib member 7, substantially as an entirety, is adapted to nest in the brace member 8. To provide for the nesting of the rib member 7 within the brace member 8 the latter, when of the form shown in Fig. 1, is substantially U-shaped in cross section.

The brace member 8 is of compound curvature, and as before stated, substantially U-shaped in cross section. The lower end of the brace member 8 is formed with a pair of extensions 11 which are clamped around the lower end of the rib member 7, the latter being provided with an eye 12 for connecting the umbrella cover 13 thereto. The brace member 8 is furthermore provided intermediate the ends thereof with a pair of extensions 14 which are clamped around the rib member 7. The clamping of the extensions around the rib member 7 is had in such manner as to form a sliding connection between the two members. That portion of the member 8 between the extensions 14 and its upper end is substantially convex in contour when the umbrella is extended, while that portion between the extensions 14 and the extensions 11 is substantially concave in contour when the umbrella is extended. The brace member 8 gradually decreases in width from the extensions 14 to its upper end and the same construction is provided in connection with the upper portion of the rib member 7. This construction increases the flexibility of the upper portion of the said members so that when the rib is released it will be automatically projected away from the stick so that the operation of opening the umbrella will be vastly facilitated. When the rib is moved to closed position, or rather retained in parallelism with respect to the stick, tension will be stored in the upper portion of the brace member and consequently when the latter is released the rib will be projected automatically from the stick. The upper end of the brace member 8 is pivotally connected to the notched collar, as at 15^a.

In Fig. 7 of the drawings a modified form of brace member is illustrated and which is indicated by the reference character 15. The member 15 is formed tubular a portion of its length, as at 16, said tubular portion surrounding the rib member 7. The eye of the rib member 7 to which the cover is attached projects through a slot 17 formed in the lower end of the brace member 15. The upper portion 18 of the brace member 15 is sub-

stantially U-shaped in contour and terminates in the tubular portion 16. The portion 18 gradually decreases in width toward its upper end.

From the manner of setting up the rib member 7 with respect to the brace member 8 it is evident that one member reinforces the other and that furthermore when the umbrella is extended and a sudden gust of wind strikes the cover the umbrella is prevented from collapsing or turning inside-out owing to the fact that the members between the extensions 14 and 11 will bow in an opposite direction with respect to each other, the rib member bowing in a concave manner and the brace member bowing in a convex manner, consequently setting up an unusually rigid rib and preventing the same from bowing in a concave manner as an entirety, thus preventing the umbrella from turning inside-out. 85

When a rib embodying a rib member 7 and a brace member 15 is used the inclosing of the rib member by the brace member will prevent the bowing of the members in an opposite direction with respect to each other in case of the umbrella being struck by a heavy gust of wind, yet the brace member will be reinforced by the rib member to such an extent as to prevent the bowing of the rib proper in either direction to an extent which would cause the collapsing or turning inside-out of the umbrella. 95

In the rib and brace shown in Patent No. 854,663 the brace member is of a length as to terminate at the upper portion of the rib member, the lower end of the brace member being fixed to the rib member. This construction does not provide means for bracing that portion of the rib member below the point of connection between the lower end of the brace member and upper portion of the rib member. A rib as herein disclosed provides means for reinforcing the rib member from the point of connection between it and the brace member to the lower end of the rib, and by such reinforcement additional rigidity is given to the rib so as to prevent the umbrella from collapsing or turning inside-out when the umbrella is struck by a sudden gust of wind. 115

An advantage possessed by an umbrella rib in accordance with this invention is that when the umbrella is closed there is less liability of the cover being cut by the ribs owing to the fact that the ribs are substantially cylindrical in cross section, presenting no sharp corners which will be liable to cut the cover as is the case in the ordinary U-shaped rib now in general use. 120

A further advantage of setting up a rib embodying a brace member and a rib member is that it enables the pivoted ends of the said members to be positioned in close proximity to the outer end of the stick than is the case with the umbrellas now in vogue. Such ar- 125

angement provides a greater covering area as the shoulders of the user can extend further within the umbrella than is the case with the umbrellas now in general use as the bridge 5 in the umbrellas now in use is arranged further from the outer end of the stick than the pivotal connections for the rib in accordance with this invention.

What I claim is—

- 10 1. An umbrella rib comprising a rib member and a brace member, said brace member provided with means embracing the rib member whereby the said members are connected together, the upper end of the brace member 15 being free of the upper end of the rib member.
2. An umbrella rib comprising two members, one of said members formed with a pair of extensions at one end and with another 20 pair of extensions at a point removed from the other end, said pairs of extensions overlapping the other member at one end and at a point removed from its other end, said pairs of extensions providing means whereby 25 when pressure is applied to the rib when the umbrella is extended, portions of the members between the said pairs of extensions will bow in opposite directions with respect to each other.
- 30 3. An umbrella rib comprising a rib member and a brace member said brace member provided with a pair of extensions at its lower end and a pair of extensions at a point removed from its upper end, said extensions 35 adapted to overlap the rib member, thereby connecting the rib member to the brace member, that portion of the brace member from the upper pair of extensions projecting in a curvilinear manner with respect to the 40 upper portion of the rib member.
4. An umbrella rib comprising a rib member and a brace member said brace member provided with a pair of extensions at its lower end and a pair of extensions at a point 45 removed from its upper end, said extensions adapted to overlap the rib member thereby connecting the rib member to the brace member, that portion of the brace member from the upper pair of extensions projecting 50 in a curvilinear manner with respect to the upper portion of the rib member, said rib member provided with an eye projecting from the brace member to which is adapted to be secured the umbrella cover, that portion 55 of the brace member projecting from the upper pair of extensions constituting a support for the umbrella, above the upper point of connection between the rib member and brace member.
- 60 5. An umbrella rib comprising a rib member and a brace member said brace member provided with a pair of extensions at its lower end and a pair of extensions at a point 65 removed from its upper end, said extensions adapted to overlap the rib member thereby connecting the rib member to the brace member, that portion of the brace member from the upper pair of extensions projecting in a curvilinear manner with respect to the upper portion of the rib member, said rib 70 member provided with an eye projecting from the brace member and to which is adapted to be secured the umbrella cover, that portion of the brace member projecting from the upper pair of extensions constituting a support for the umbrella, above the upper point of connection between the rib member and brace member.
7. The combination with the runner of an umbrella and the notched collar of an umbrella which is secured to the umbrella stick, of an umbrella rib embodying a rib member and a brace member, said brace member connected to said collar and said rib member connected with said runner, said rib member 80 of a length as to extend in close proximity to the lower end of the brace member, said brace member provided with means for connecting the major portion of the rib member thereto, the upper portion of the brace member 85 projecting away from the upper portion of the rib member in a curvilinear manner.
8. The combination with the runner of an umbrella and the notched collar of an umbrella which is secured to the umbrella stick, of an umbrella rib embodying a rib member, and a brace member, said brace member connected to said collar and said rib member connected with said runner, said rib member 90 of a length as to extend in close proximity to the lower end of the brace member, said brace member provided with means for connecting the major portion of the rib member thereto, the upper portion of the brace member 95 projecting away from the upper portion of the rib member in a curvilinear manner.
9. The combination with the runner of an umbrella and the notched collar of an umbrella which is secured to the umbrella stick, of an umbrella rib embodying a rib member, and a brace member, said brace member connected to said collar and said rib member connected with said runner, said rib member 100 of a length as to extend in close proximity to the lower end of the brace member, said brace member provided with means for connecting the major portion of the rib member thereto, the upper portion of the brace member 105 projecting away from the upper portion of the rib member in a curvilinear manner, said rib member provided with an eye projecting from the lower portion of the brace member and providing means to which the umbrella cover can be attached, that portion of the 110 brace member which projects from the upper portion of the rib member constituting a support for the cover.
- In testimony whereof I have hereunto set my hand in presence of two subscribing witnesses.

MICHAEL G. MCGUIRE.
